UNITED STATES PATENT OFFICE.

PHILIP ZALKIND, OF NEW YORK, N. Y.

CONTAINER.

1,389,923.

Specification of Letters Patent.

Patented Sept. 6, 1921.

Application filed April 23, 1918. Serial No. 230,204.

To all whom it may concern:

Be it known that I, PHILIP ZALKIND, a citizen of the United States, residing in the city and State of New York, have invented 5 an Improvement in Containers, of which the following is a specification.

This invention relates to a container or package. The particular form of container or package to which the invention relates is 10 that type of such articles in which commonly various articles of food, such as cereals and spices, for example, as well as certain drugs in powdered form or otherwise, are sold. As heretofore employed, in 15 containers or packages of this general type, the ends of the package are so closed as to make it necessary to break them or any other wall of the package, in order to gain access to the contents thereof, and when so broken 20 the removal or dispensing of the contents of the container therefrom is likely to be promiscuous and uncertain. Now, the object of this invention is to provide in a container or package preferably as an integral 25 part of the wall or walls thereof, a dispensing trough or chute which normally maintains the package in a closed condition and which may be turned outwardly to provide an aperture in the package as well as a 30 trough for dispensing its contents, and in the present case, the invention also includes a measuring device or apparatus by which in dispensing the contents of the package a predetermined quantity or measure of the 35 contents may be obtained at each operation. This as will be apparent is important and advantageous in measuring for example sugar, salt, or various forms of cereals, as well as numerous forms of drugs. The form 40 of container comprising the present invention will be hereinafter more particularly described in conjunction with the accompanying drawing, in which:

Figure 1 is a side elevation of a container 45 in which the present invention is embodied showing the flaps turned up.

Fig. 2 is a central view of the flaps closed.

Fig. 3 is a plan of the parts as shown in Fig. 1.

Fig. 4 is a section on line 4—4 Fig. 3, and

Fig. 5 is a plan view of the blank from which the measuring device is formed.

Referring to Figs. 1 to 5 inclusive, in which I have illustrated more or less dia- 55 grammatically a form of container in which my present invention may be embodied, 10 indicates the container, and 11 one side wall

thereof, while 12 is the flap formed of a continuation of the wall 11, and 13 and 14 are flaps formed of continuations of the front 60 and rear walls respectively, it being understood that the opposite side wall has the flap corresponding to the flap 12. It will furthermore be understood that the container may be made of paper cardboard, or 65 any other similar material of which like articles are commonly made.

The crease line between the side 11 and its flap 12 as indicated at 15 and in the side wall 11 I also provide a crease line 16. 70 This side wall 11 is also scored along the perforated line 17 and the flap 12 is cut along the lines 18, 19, 20 and 21, the cut 18 preferably being a continuation of the perforated line 17 and the cut line 19, a straight 75 line continuation of the cut line 18, the cut line 20 being at right angles to the cut line 19 and the cut line 21 at right angles to the cut line 20 and terminating in a curved cut line at a point in the crease line 15 as clearly 80 indicated in Fig. 1. In creasing, scoring, and cutting the side member 11 and its flap 12 in this manner, there is formed a flap 22 and a tongue 23 therein, the flap 22 being bounded by the crease line 16, the perforated 85 line 17 and a portion of the crease line 15, while the tongue 23 is outlined by the cut lines 18, 19, 20 and 21.

Together with the parts of the container as hereinbefore described, I employ a measuring device. This is conveniently made from a blank of the same or similar material to that of which the container is made, and in the form illustrated in Fig. 5. This measuring blank as indicated at 24 is generally 90 triangular in outline and is provided with crease lines 25, 26, and 27, so as to divide the blank into triangular side members 28, 29, 30 and 31. The side member 28 provided with an extension or tongue 33 95 by means of which and a suitable adhesive material, when the parts are folded, the side 28 may be secured to the side 31. This as will be understood, when the parts are thus connected, forms a conical vessel which may 100 be used as a measuring device. A portion of the side member 29 as indicated in the dotted lines in Fig. 5, is secured to the inner face of the tongue 23 by a suitable adhesive material or otherwise, so as to assume the 110 position indicated in Fig. 1. In this position, as will be understood, the side 28 lies against the side 29 and the side 31 against the side 30 so that the parts may assume the

flat position for packing, shipping, or other similar purposes.

Now, with a container thus formed, and filled, the end flaps 12 are turned to position 5 and then the front and rear flaps 13 and 14 folded to place and secured to one another, into which condition as will be understood, the package is sealed and ready for sale. In the use of the package the side 11 is 10 broken along the perforated line 17, and the flap 22 turned on the crease line 16. In so doing, as will now be apparent, the measuring device which has been opened by turning the flap 12 to place, may be swung outwardly together with the flap 22 and the tongue 23 which parts, being folded along a portion of the crease line 15 form a trough for pouring from the contents that portion thereof which may be contained in the 15 measure 24.

As hereinbefore stated, the invention in the present case is merely herein shown and described in a diametric manner, as various modifications may obviously be made without departing from the nature and spirit of 20 this invention.

I claim as my invention:

1. In a container, inclosing walls, a trough formed in predetermined walls of the container and adapted to be separated in part therefrom and to be swung to provide an opening and form a chute for removing the contents of the container, and a measuring device connected to and operated by the said 35 trough which forms a chute for the discharge of the contents of the measuring device.

2. In a container, inclosing walls, a tongue member provided in predetermined walls of the container normally closing the same and 40 adapted to be separated in part therefrom along predetermined lines to provide an aperture and form a trough which opens and closes the said aperture, and a measuring device associated with the said tongue member and adapted to determine the amount of the 45 contents of the container which is removed therefrom along the said trough at each operation thereof.

3. In a container, inclosing walls, a tongue member provided in predetermined walls of the container normally closing the same and adapted to be separated in part therefrom along predetermined lines to provide an aperture and form a trough which opens and 55 closes the said aperture, a stop included in a wall of the trough for determining the extent of the movement thereof, and a measuring device associated with the said tongue member and adapted to determine the 60 amount of the contents of the container which is removed therefrom along the said trough at each operation thereof.

4. In a container, inclosing walls, a tongue member provided in predetermined adjacent 65 walls of the container and adapted to be

separated in part therefrom along predetermined lines to provide an aperture and form a trough which opens and is adapted to close the said aperture, and a measuring device associated with the said tongue member and 70 adapted to determine the amount of the contents of the container which is removed therefrom along the said trough at each operation therefor, the said measuring device being adapted to lie parallel with the walls 75 from which the container is formed when in a flat or unassembled condition and to open and automatically assume its position for use when the walls of the container are folded to form the same.

5. In a container, inclosing walls adapted to be formed from an integral blank and to lie flat when in an unassembled condition, a tongue member provided in predetermined adjacent walls of the container, normally 80 closing the same and adapted to be separated in part therefrom along predetermined lines to provide an aperture and form a trough which opens and is adapted to close the said aperture, and a measuring device 85 comprising a member made of triangular shaped sides associated with the said tongue and adapted to lie flat or parallel with the walls of the container when the parts are unassembled and to automatically open to position for use when the walls of the container are folded to form the same, the said measuring device being adapted to determine the amount of the contents of the container 90 which is removed therefrom along the said 100 trough at each operation thereof.

6. In a container having walls adapted to lie flat and to be folded to position in setting up the container for use, means whereby the contents of the container are removable 105 therefrom, and a measuring device associated with the walls of the container and the aforesaid means and adapted to be collapsed when the walls of the container lie flat against one another and to be opened for use when the walls of the container are set up to position for use.

7. In a container having walls adapted to lie flat against each other and to be folded to position in setting up the container for use, 115 means whereby the contents of the container are removable therefrom, and a measuring device associated with the said means and a wall of the container and adapted to be collapsed when the walls of the container lie 120 against each other and to be opened to cooperate with the said means and the walls of the container when the latter are set up for use so that the said measuring device is adapted to receive and remove a quantity of 125 the contents of the container each time the said means are operated.

Signed by me this 17th day of April, 1918.

PHILIP ZALKIND.
